**RULE FOR MEASURING AREAS AND VOLUMES
IN ESTIMATING EARTH WORK QUANTITY IN
HIGHWAY DESIGN AND LIKE ENGINEERING
APPLICATIONS**

Franklin Le Roy Davis, 592 Oakley St.,
Salt Lake City, Utah

Filed Sept. 11, 1959, Ser. No. 57,512

Term of patent 14 years

(Cl. D52—1)

Fig. 1 is a top perspective view of a rule for measuring areas and volumes in estimating earth work quantity in highway design and like engineering applications, showing my new design.

Fig. 2 is a bottom perspective view thereof.

I claim:

The ornamental design for a rule for measuring areas and volumes in estimating earth work quantity in highway design and like engineering applications, as shown.
